[57] CLAIM

The ornamental design for a article hanger, as shown and described.

DESCRIPTION

FIG. 1 is an environmental perspective elevational view of an article hanger showing my new design;

FIG. 2 is a front elevational view thereof;

FIG. 3 is a rear elevational view thereof;

FIG. 4 is a top view thereof;

FIG. 5 is a left side elevational view with the right side being a mirror image thereof;

FIG. 6 is a bottom view thereof;

FIG. 7 is a front elevational view of an alternative article hanger showing my new design;

FIG. 8 is a rear elevational view thereof;

FIG. 9 is a top view thereof;

FIG. 10 is a left side elevational view with the right side being a mirror image thereof; and,

FIG. 11 is a bottom view thereof.

The broken line showing of the automobile and the articles is for illustrative purposes only and forms no part of the claimed design. The main bar is divided to indicate a varying number of bag holding hooks.
